DESIGN FOR A WALL BRACKET FOR ELECTRIC LIGHT

Alfred Easton Poor, Locust, N. J., assignor to
Pass & Seymour, Inc., Syracuse, N. Y., a cor-
poration of New York

Application September 20, 1939, Serial No. 87,306

Term of patent 14 years

To all whom it may concern:

Be it known that I, Alfred Easton Poor, a citizen of the United States and resident of Locust, county of Monmouth, and State of New Jersey, have invented a new, original, and ornamental Design for a Wall Bracket for Electric Light, of which the following is a specification, reference being had to the accompanying drawing forming a part thereof, and in which:

Figure 1 is a front elevation of a wall bracket for electric light showing my new design;
Figure 2 is a side elevation thereof; and
Figure 3 is a bottom plan view thereof.

I claim:

The ornamental design for a wall bracket for electric light, substantially as shown.

ALFRED EASTON POOR.
